UNITED STATES PATENT OFFICE.

JAMES GATES, OF MONTREAL, QUEBEC, CANADA.

FURNACE CONSTRUCTION.

Application filed October 4, 1920. Serial No. 414,672.

To all whom it may concern:

Be it known that I, JAMES GATES, a subject of the King of Great Britain, and resident of the city of Montreal, in the Province 5 of Quebec and Dominion of Canada, have invented certain new and useful Improvements in Furnace Construction, of which the following is a full, clear, and exact description.

10 This invention relates to improvements in furnace construction, and the object of the invention is to provide a novel refractory lining for furnaces and a novel method of securing the same in the furnace.

15 A further object is to provide a lining which will be readily removed for renewal without damage to the furnace wall.

20 A still further object is to provide a furnace lining so constructed that it will not be projected into the furnace by accumulations of grit falling behind it.

25 The invention consists briefly in providing a furnace having a suitably shaped recess therearound extending from the level of the grate upwardly. The lining is composed of a series of blocks, each in two co-operating parts arranged one above the other and each engaging in the furnace wall in a manner to hold them against tilting into 30 the furnace.

35 In the drawings which illustrate the invention:—

Fig. 1 is a perspective view of a furnace constructed according to this invention partly broken away in section.

40 Fig. 2 is a vertical sectional view illustrating the lining construction and arrangement.

Fig. 3 is an end elevation of a modified form of block.

45 Referring more particularly to the drawings, 11 designates the wall forming a boiler furnace and 12 the grates. The wall of this furnace is provided from the level of the grate upwards with a recess 13 which extends around the furnace from side to side of the doorway and, if desired, through the doorway itself to the outer surface of the wall. The upper and lower parts of the 50 recess, designated 14 and 15 respectively, are deeper than the intermediate portion.

55 The lining of the furnace consists of a plurality of composite blocks 16 each comprising upper and lower parts 17 and 18 respectively, preferably inclined at their

meeting edges 19. Each block part is substantially L-shaped in cross section, as clearly shown in Figure 2, and what may be considered the tail portions 20 of the L's are thinner than the stem portions 21. These 60 tail portions are preferably the thickness of a standard brick and adapted to fit easily and yet firmly in the deepened upper and lower portions 14 and 15 of the recess, as clearly shown in Figure 2, while the stem 65 portions 21 of the block parts occupy the main portion of the recess, completely filling the same so that the face 22 of the block is flush with the surface of the wall. The recess also extends a short distance below the 70 deep lower portion 15 to receive a stretcher course 23 of brick. If desired, the recess may be also continued above the upper deepened portion 14 to receive another stretcher course 24. It will be understood, 75 however, that only one such stretcher course is necessary to the invention. The meeting edges of the block parts are preferably of tongue and groove construction, as shown at 25, but it will be understood that this is 80 not essential. The lower part 18 of the block is preferably constructed of carborundum or other suitable highly refractory material. The upper part 17 may be constructed of any good refractory, such as fire 85 clay, or may be of the same material as the lower part of the block. The vertical edges of the block may be formed in any suitable manner to prevent the passage of flame and gas between the blocks when the same are 90 in place.

95 In building the furnace, the recess is constructed as previously described and the block parts inserted, the lower part first and the upper part afterwards. When the blocks become burned out, they may be readily renewed without interfering with or in any way destroying the wall construction, owing to the shallowness of the recess. In removing burnt out blocks, 100 either of the stretcher courses 23 or 24 may be removed if necessary to give the block parts limited movement sufficient to enable the groove and tongue connection 25 to be disengaged and permit the upper portion 105 17 of a block to be withdrawn. The lower portion is then withdrawn and a new lower portion inserted. The top part is then inserted and lastly the stretcher course if it has been removed. The stretcher course, 110

together with the grouting of fire clay or the like inserted between it and the wall and between it and the block, will hold the upper and lower block parts sufficiently close together so that the groove and tongue construction will prevent the upper part working out of the recess. As the greater part of the burning out will occur in the lower part of the block, it may be possible to use the upper part again. This will depend to a large extent upon the depth and character of the fire and, in order to deal economically with fires of all descriptions, the upper and lower parts of the block may be of different relative sizes. That is to say, the vertical measurement of the upper part 17 may be much greater relatively to the vertical measurement of the lower part than shown in the drawings. It is preferable, however, that the parts bear approximately the relation illustrated in Figure 2, since to a certain extent the mechanical operation of the block depends upon this.

The movement in any boiler setting due to vibration and to expansion and contraction causes a certain amount of grit to work off the blocks, and it has been found that this grit tends to accumulate behind lining blocks and force the same into the furnace.

The movement of the blocks is usually a tipping one. In the present construction, the foot 20 of the upper block which projects rearwardly from the rear face of the block excludes from the back of the block all grit falling from above the block. The only grit which can accumulate behind the block is therefore that which originates behind the block itself. Any tendency of the lower part of the block to tip outwardly due to such an accumulation of grit is of course resisted by the upper part of the block, which holds the lower part both by the tongue and groove engagement and by the slope of the meeting faces. The tendency to outward swing of the lower block part produces a similar tendency in the upper part, and this tendency in both parts is resisted by the rearwardly projecting tails 20 of the parts engaging in the deeper portions of the wall recess. The block parts will of course tend to swing about their upper and lower edges respectively on the stretcher courses 23, 24. When either of these courses is removed, it will be understood that sufficient freedom of movement will be given the parts to enable their separation for removal. The re-insertion of the stretcher course, together with the grouting or chinking of fire-clay, will hold the parts securely in interlocking position. If the tongue and groove connection is sufficiently shallow, as shown in Figure 2, it may not be necessary to remove either stretcher course, as removal of the grouting above and below the block will permit

sufficient movement of the block parts to clear the tongue over the front lip of the groove.

The precise form of the blocks may be subject to a number of modifications which cannot be all described at length. As illustrative of such modifications, there is shown in Figure 3 a block having the upper and lower parts 17^a and 18^a thereof rabbed as at 19^a instead of meeting in an inclined plane, as shown in the other figures. In any form of the block, the recess in the furnace wall is so shallow that the wall above the recess is self supporting without any special construction such as a cornice.

Having thus described my invention, what I claim is:—

1. A furnace wall having a recess extending therearound from the level of the grate upward, said recess being deeper immediately adjacent the top and bottom walls than in the intervening portion, and lining blocks inserted in said recess having rearwardly projecting portions forming continuations of the top and bottom surfaces of the blocks and engaging the deeper parts of the recess to hold the blocks against tipping into the furnace.

2. A furnace wall having a recess extending therearound from the level of the grate upward, said recess being deeper at top and bottom than in the intervening portion, and lining blocks inserted in said recess having rearwardly projecting portions engaging the deeper parts of the recess to hold the blocks against tipping into the furnace, each block being composed of upper and lower parts adapted to interlock and hold in such interlocking relation when in the wall recess.

3. A furnace wall having a recess extending therearound from the level of the grate upward, said recess being deeper at top and bottom than in the intervening portion, and lining blocks inserted in said recess having rearwardly projecting portions engaging the deeper parts of the recess to hold the blocks against tipping into the furnace, each block being composed of upper and lower parts having inclined meeting edges.

4. A furnace wall having a recess extending therearound from the level of the grate upward, said recess being deeper at top and bottom than in the intervening portion, and lining blocks inserted in said recess having rearwardly projecting portions engaging the deeper parts of the recess to hold the blocks against tipping into the furnace, each block comprising upper and lower portions having inclined meeting edges, the inclination being in a plane sloping downwardly toward the furnace, the meeting edges of said blocks being tongued and grooved.

5. A furnace wall having a recess extend-

ing therearound, said recess being deeper at top and bottom than in the intervening portion, lining blocks inserted in said recess having rearwardly projecting portions engaging the deeper parts of the recess to hold the blocks against tipping into the furnace, each block comprising upper and lower portions adapted for interlocking engagement in the recess, and a removable 10 stretcher course in the wall at a longitudinal edge of the recess normally holding the block parts in interlocking relation and removable to permit movement of the block parts for disengagement.

15 6. A block comprising upper and lower parts, a rearwardly extending flange at the upper part of the upper block and a rearwardly extending flange at the lower part

of the lower block, said flanges being adapted for engagement in recesses of a furnace 20 wall to hold the block parts against tipping into a furnace, one of said block parts being formed to overlie the other part to hold the same against tipping into a furnace.

7. A furnace lining block comprising upper and lower parts, said parts meeting in a plane inclined downwardly from the rear surface of the block to the front surface.

8. A furnace lining block comprising upper and lower parts, the upper part depending at the front surface below the top of the lower part at the rear surface.

In witness whereof, I have hereunto set my hand.

JAMES GATES.
